UNITED STATES PATENT OFFICE.

CORNEIL RIDDERHOF, OF GRAND RAPIDS, MICHIGAN, ASSIGNOR TO THE WILMARTH & MORMAN COMPANY, OF GRAND RAPIDS, MICHIGAN.

DRILL-GRINDING MACHINE.

SPECIFICATION forming part of Letters Patent No. 743,083, dated November 3, 1903.

Application filed January 8, 1903. Serial No. 138,226. (No model.)

To all whom it may concern:

Be it known that I, CORNEIL RIDDERHOF, a citizen of the United States, residing at the city of Grand Rapids, in the county of Kent and State of Michigan, have invented certain new and useful Improvements in Drill-Grinding Machines, of which the following is a specification.

This invention relates to improvements in drill-grinding machines. It has to do with the arrangement and manipulation of the grinding-wheel rather than with the holder for the drill, the holder adopted being similar to that shown in the patent issued to Henry P. White on February 20, 1900, No. 643,703.

In the style of drill-grinders most commonly on the market at the present time the grinding is accomplished on the radial face of the wheel as distinguished from its periphery, and this necessitates a special construction of wheel which is copped out at the center and is not so easily obtained as the emery-wheels in ordinary use for other purposes, and owing to the special features there is a considerable advance in the price of such grinding-wheels.

It is the object of my invention to provide a means whereby the standard regular form of emery or other grinding wheels is made available.

Second. In the common form of drill-grinders a comparatively large surface of the drill-point is exposed to the grinding-wheel, which traverses lengthwise of the lip rather than across the same, thereby generating by the abrasive action a considerable amount of heat, and as the motion of the surface of the wheel is not directly away from the edge to be ground this heat is liable to soften the cutting edge. It is my purpose to avoid this contingency by the special arrangement of the grinding-wheel in relation to the holder, as aforesaid, so that the heat will be carried away from the edge and this contingency avoided.

Third. It is also my purpose to overcome the difficulty of grooving or creasing the grinding-wheel, which is now so likely to occur unless great pains is taken in the adjustment of the drill-holder, by providing a recip-

rocating means which will constantly shift the cutting-surface of the wheel in its relation to the drill-point and keep the surface straight without requiring truing or dressing.

Fourth. It is my object to arrange the grinding-wheel in its relation to the holder in such a manner that the whole is freely illuminated, so that the workman can see exactly what is taking place in the grinding operation.

Fifth. It is my object to arrange the grinding-wheel in its relation to the drill-point in such manner that the same can be readily inspected without danger from the flying sparks from the grinding-wheel; sixth, to provide improved connections whereby the relative height of the grinding-wheel and drill-holder may be varied to properly accommodate different sizes of drills within the holder, so that the periphery of the grinding-wheel will be worn away evenly and the entire point of the drill will be properly ground.

Further objects relating to details will definitely appear in the detailed description to follow. I accomplish the objects of my invention by the devices and means described in the following specification.

A structure embodying the features of my invention is clearly illustrated in the accompanying drawings, forming a part of this specification, in which—

Figure 1 is a side elevation view of a drill-grinding machine embodying the features of my invention. Fig. 2 is a front elevation view of the same with the drill-holder H detached and removed. Fig. 3 is a sectional plan view taken on line 3 3 of Fig. 2 of the structure as it is illustrated in Fig. 2, the drill-holder being omitted. Fig. 4 is an enlarged vertical detail sectional view taken on a line corresponding to line 4 4 of Fig. 2, showing the reciprocating means for reciprocating the grinding-wheel up and down and the method of its adjustment, the driving-pulley, the central standard G, the spindle for the grinding-wheel D, and the stud I being shown in full lines. Fig. 5 is an enlarged detail sectional view on the irregular line 5 5 of Fig. 2 through the reciprocating gearing and vertical adjusting means for the spindle of the driving-wheel. Fig. 6 is a detail view

- of the lower end of the screw-adjusting rod C for varying the elevation of the grinding-wheel. Fig. 7 is a detail cross view of the drill-holder H, showing its V-shaped form.
- 5 In the drawings all of the sectional views are taken looking in the direction of the little arrows at the ends of the section-lines, and similar letters of reference refer to similar parts throughout the several views.
- 10 Referring to the lettered parts of the drawings, the main frame A is provided with a suitable base, which carries bracket-boxings B' B' for the driving-shaft B of the machine. A tight and loose pulley C' is provided for connection to the power. A pulley C is on the shaft B, which drives the spindle D by means of a suitable belt turning at right angles over idlers F and running to pulley E'. The pulley E' is secured by a suitable set-
15 screw on the sleeve E, and this drives the spindle D by means of a suitable feather *e* in a suitable featherway, so that the spindle D while it is rotated may be freely reciprocated up and down. On the upper end of the spindle D is the horizontal grinding-wheel D'. The stud I is provided on the frame A, to which the drill-holder is secured, in the same manner as that described in the Letters Patent to Henry P. White referred to above.
- 20 The holder H is the same in all essential particulars and is adjustable for holding the drill in the same manner. The grinding-wheel, however, is placed with its axis vertically and the point of the drill is brought into contact with the periphery of the same, as clearly appears in Fig. 1. A plunger G is provided in the main frame A, and the grinding-wheel spindle D rests upon it, so that when this plunger is reciprocated up and
25 down the wheel-spindle D moves up and down with it. The plunger G is connected by a pitman G' to the wrist-pin on the gear-wheel *a'*. The gear-wheel *a'* is carried on a suitable journal *b*, secured to an arm J, which
30 arm is secured or is integral with a sleeve J', which embraces the driving-shaft B of the machine. On the end of the driving-shaft B is a small pinion *a*, meshing with the gear-wheel *a'*, thereby actuating the same through
35 the pitman G' constantly reciprocating the wheel-spindle D by its actuation of the plunger G. The arm J is adjustable up and down and by the screw-rod *c*, extending through a suitable eye *c'*, secured to the outer
40 end of the arm J. A hand-wheel *c''* is on the upper end of the rod *c*, which extends through a suitable bracket on the main frame A at a point convenient to the hand of the operator. It will thus be seen that we have here an
45 effective drill-grinder in which the periphery of the grinding-wheel is made use of as an abrading-surface, thereby using the grinding-wheel in exactly the same manner as it is ordinarily used.
- 50 A special means is provided for reciprocating the holder up and down, thereby insuring even wearing of the grinding-wheel, so that

the points of all drills presented to the same will be ground smooth and true.

Owing to the fact that the holder is V-shaped, different sized drills when placed within the same will reach to different heights in relation to the grinding-wheel, and therefore an adjustment is provided for varying the elevation at which the grinding-wheel reciprocates to accommodate this varying elevation of the drill-points. As the grinding-wheel in this position turns rapidly away from the drill-point, there is no danger of unduly heating the cutting edge.

I have shown my improved drill-grinder in the form in which it is preferred by me. I am aware, however, that the details of construction can be greatly varied without departing from the broad features of my invention. There are a great variety of means of making the wheel-spindle adjustable up and down or of reciprocating it up and down in a revolving sleeve or pulley or other rotatable part.

I have shown means preferably adjusting the grinding-wheel to the proper elevation, though any means that would change the relative position of the drill-holder and grinding-wheel could be employed in this relation.

Where I have shown gearings, other driving means might be employed, and it is obvious that this drill-grinding machine would be adapted to direct electrical connection, it being unnecessary for me to illustrate the same for the purposes of this patent.

Having thus described my invention, what I claim as new, and desire to secure by Letters Patent, is—

1. In a drill-grinding machine, the combination of the main frame A; a vertical adjustable and reciprocating wheel-spindle D supported therein, with a horizontal grinding-wheel D' thereon; a V-shaped drill-holder H supported on a suitable stud I in position to present the point of the drill to the periphery of the grinding-wheel; a suitable driving-shaft B with belt connections to a pulley and sleeve embracing the wheel-spindle D, and feathered thereon, whereby the same can be reciprocated up and down; a plunger G beneath the wheel-spindle D for reciprocating the same up and down; a pitman G' connected to the lower end of the plunger G; a gear-wheel *a'* to the wrist-pin of which the lower end of the pitman G' is connected; a pinion *a* on the end of the driving-shaft for actuating the gear-wheel *a'*; a sleeve J' embracing the driving-shaft, with a lateral arm J carrying a suitable journal *b* on which the gear *a'* revolves; a screw-rod *c* connected to a pivoted eye *c'* on the arm J with a hand-wheel *c''* for adjusting the same, all coacting together substantially as described and for the purpose specified.

2. In a drill-grinding machine, the combination of the main frame A; a vertical adjustable and reciprocating wheel-spindle D supported therein, with a horizontal grind-

- ing-wheel D' thereon; a V-shaped drill-holder H supported in position to present the point of the drill to the periphery of the grinding-wheel; a suitable driving-shaft B with belt connections to a pulley and sleeve embracing the wheel-spindle D, and feathered thereon, whereby the same can be reciprocated up and down; a plunger G beneath the wheel-spindle D for reciprocating the same up and down; 5 a pitman G' connected to the lower end of the plunger G; a gear-wheel a' to the wrist-pin of which the lower end of the pitman G' is connected; a pinion a on the end of the driving-shaft for actuating the gear-wheel a'; a sleeve J' embracing the driving-shaft, with a lateral arm J carrying a suitable journal b on which the gear a' revolves; means for adjusting the same, substantially as described. 10 3. In a drill-grinding machine, the combination of the main frame A; a vertical adjustable and reciprocating wheel-spindle D supported therein, with a horizontal grinding-wheel D' thereon; a V-shaped drill-holder H supported on a suitable stud I in position 15 to present the point of the drill to the periphery of the grinding-wheel; a suitable driving-shaft B with belt connections to a pulley and sleeve embracing the wheel-spindle D and feathered thereon, whereby the same can be reciprocated up and down; a plunger G beneath the wheel-spindle D for reciprocating the same up and down; a pitman G' connected to the lower end of the plunger G; a gear-wheel a' to the wrist-pin of which the lower 20 end of the pitman G' is connected; a pinion a on the end of the driving-shaft for actuating the gear-wheel a'; a screw-rod c connected to a pivoted eye c' on the arm J with a hand-wheel c'', substantially as described. 25 4. In a drill-grinding machine, the combination of the main frame A; a vertical reciprocating wheel-spindle D supported therein, with a horizontal grinding-wheel D' thereon; a drill-holder H supported on a suitable stud I in position to present the point of the drill to the periphery of the grinding-wheel; a suitable driving-shaft B with belt connections to a pulley and sleeve embracing the wheel-spindle D, and feathered thereon, whereby the 30 same can be reciprocated up and down; a plunger G beneath the wheel-spindle D for reciprocating the same up and down; a pitman G' connected to the lower end of the plunger G; a gear-wheel a' to the wrist-pin of which the lower end of the pitman G' is connected; a pinion a on the end of the driving-shaft for actuating the gear-wheel a'; a screw-rod c connected to a pivoted eye c' on the arm J with a hand-wheel c'', substantially as described. 35 5. In a drill-grinding machine, the combination of the main frame A; a vertical reciprocating wheel-spindle D supported therein, with a horizontal grinding-wheel D' thereon; a drill-holder H supported on a suitable stud I in position to present the point of the drill to the periphery of the grinding-wheel; a suitable driving-shaft B with belt connections to a pulley and sleeve embracing the wheel-spindle D, and feathered thereon, whereby the same can be reciprocated up and down; a plunger G beneath the wheel-spindle D for reciprocating the same up and down; a pitman G' connected to the lower end of the plunger G; a gear-wheel a' to the wrist-pin of which the lower end of the pitman G' is connected; means for driving said gear-wheel a'; a screw-rod c connected to the pivoted eye c' on the arm J with a hand-wheel c'', substantially as described. 40 6. In a drill-grinding machine, the combination of the main frame A; a vertical reciprocating wheel-spindle D supported therein, with a horizontal grinding-wheel D' thereon; a drill-holder H supported on a suitable stud I in position to present the point of the drill to the periphery of the grinding-wheel; a suitable driving-shaft B with belt connections to a pulley and sleeve embracing the wheel-spindle D, and feathered thereon, whereby the same can be reciprocated up and down; a plunger G beneath the wheel-spindle D for reciprocating the same up and down; a pitman G' connected to the lower end of the plunger G; a gear-wheel a' to the wrist-pin of which the lower end of the pitman G' is connected; means for driving said gear-wheel a'; a screw-rod c connected to the pivoted eye c' on the arm J with a hand-wheel c'', substantially as described. 45 7. In a drill-grinding machine, the combination of the main frame A; a vertical reciprocating wheel-spindle D supported therein, with a horizontal grinding-wheel D' thereon; a drill-holder H supported on a suitable stud I in position to present the point of the drill to the periphery of the grinding-wheel; a suitable driving-shaft B with belt connections to a pulley and sleeve embracing the wheel-spindle D, and feathered thereon, whereby the same can be reciprocated up and down; a plunger G beneath the wheel-spindle D for reciprocating the same up and down; a pitman G' connected to the lower end of the plunger G; a gear-wheel a' to the wrist-pin of which the lower end of the pitman G' is connected; means for driving said gear-wheel a'; a screw-rod c connected to the pivoted eye c' on the arm J with a hand-wheel c'', substantially as described. 50 8. In a drill-grinding machine, the combination of the main frame A; a vertical reciprocating wheel-spindle D supported therein, with a horizontal grinding-wheel D' thereon; a drill-holder H supported on a suitable stud I in position to present the point of the drill to the periphery of the grinding-wheel; a suitable driving-shaft B with belt connections to a pulley and sleeve embracing the wheel-spindle D, and feathered thereon, whereby the same can be reciprocated up and down; a plunger G beneath the wheel-spindle D for reciprocating the same up and down; a pitman G' connected to the lower end of the plunger G; a gear-wheel a' to the wrist-pin of which the lower end of the pitman G' is connected; means for driving said gear-wheel a'; a screw-rod c connected to the pivoted eye c' on the arm J with a hand-wheel c'', substantially as described. 55 9. In a drill-grinding machine, the combination of the main frame A; a vertical reciprocating wheel-spindle D supported therein, with a horizontal grinding-wheel D' thereon; a drill-holder H supported on a suitable stud I in position to present the point of the drill to the periphery of the grinding-wheel; a suitable driving-shaft B with belt connections to a pulley and sleeve embracing the wheel-spindle D, and feathered thereon, whereby the same can be reciprocated up and down; a plunger G beneath the wheel-spindle D for reciprocating the same up and down; a pitman G' connected to the lower end of the plunger G; a gear-wheel a' to the wrist-pin of which the lower end of the pitman G' is connected; means for driving said gear-wheel a'; a screw-rod c connected to the pivoted eye c' on the arm J with a hand-wheel c'', substantially as described. 60

rocating wheel-spindle D supported therein, with a horizontal grinding-wheel D' thereon; a drill-holder H supported on a suitable stud I in position to present the point of the 65 drill to the periphery of the grinding-wheel; a suitable driving-shaft B with belt connections to a pulley and sleeve embracing the wheel-spindle D, and feathered thereon, whereby the same can be reciprocated up and down; a plunger G beneath the wheel-spindle D for reciprocating the same up and down; means of actuating said plunger; a screw-rod c connected to a pivoted eye c' on the arm J with a hand-wheel c'' for adjusting the same, 70 substantially as described. 75

6. In a drill-grinding machine, the combination of the main frame A; a vertical reciprocating wheel-spindle D supported therein, with a horizontal grinding-wheel D' thereon; a drill-holder H supported on a suitable stud I in position to present the point of the 80 drill to the periphery of the grinding-wheel; a suitable driving-shaft B with belt connections to a pulley and sleeve embracing the wheel-spindle D, and feathered thereon, whereby the same can be reciprocated up and down; a screw-rod c connected to a pivoted eye c' on the arm J with a hand-wheel c'' for adjusting the same, 85 substantially as described. 90

7. In a drill-grinding machine, the combination of the main frame A; a vertical reciprocating wheel-spindle D supported therein, with a horizontal grinding-wheel D' thereon; a drill-holder H supported on a suitable 95 stud I in position to present the point of the drill to the periphery of the grinding-wheel; a screw-rod c connected to a pivoted eye c' on the arm J with a hand-wheel c'' for adjusting the same, substantially as described. 100

8. In a drill-grinding machine, the combination of a vertical reciprocating wheel-spindle; a grinding-wheel thereon; and a holder arranged to present the point of the drill to the periphery of the said grinding-wheel, as 105 specified.

9. In a drill-grinding machine, the combination of a suitable frame; a vertical reciprocating wheel-spindle; a horizontal grinding-wheel thereon; a V-shaped drill-holder to present the point of the drill to the grinding-wheel, and means of adjusting the elevation at which the grinding-wheel reciprocates, for the purpose specified.

In witness whereof I have hereunto set my 115 hand and seal in the presence of two witnesses.

CORNEIL RIDDERHOF. [L. S.]
